UNITED STATES PATENT OFFICE.

GLENN E. McFADDEN, OF LAKEWOOD, OHIO, ASSIGNEE TO ALFRED VESTER SONS, INC.,
OF PROVIDENCE, RHODE ISLAND, A CORPORATION OF RHODE ISLAND.

DESIGN FOR A CAST ARM FOR LIGHTING FIXTURES.

Application filed October 10, 1923. Serial No. 7,463. Term of patent 3½ years.

To all whom it may concern:

Be it known that I, GLENN E. McFADDEN, a citizen of the United States, and residing at Lakewood, in the county of Cuyahoga and State of Ohio, have invented a new, original, and ornamental Design for a Cast Arm for Lighting Fixtures, of which the following is a specification, reference being had to the accompanying drawing, forming part thereof.

Fig. 1 is a side elevation and Fig. 2 is a plan view of a cast arm showing my new design.

I claim:

The ornamental design for a cast arm for lighting fixtures as shown.

GLENN E. McFADDEN.
